(57) **CLAIM**

We claim the ornamental design for an alarm clock, as shown and described.

DESCRIPTION

FIG. 1 is a perspective view of the alarm clock of a first embodiment our new design;

FIG. 2 is a front elevational view of the alarm clock of the first embodiment;

FIG. 3 is a rear elevational view of the alarm clock of the first embodiment;

FIG. 4 is a right side elevational view of the alarm clock of the first embodiment;

FIG. 5 is a top plan view of the alarm clock of the first embodiment;

FIG. 6 is a bottom plan view of the alarm clock of the first embodiment;

FIG. 7 is a perspective view of the alarm clock of a second embodiment our new design;

FIG. 8 is a front elevational view of the alarm clock of the second embodiment;

FIG. 9 is a rear elevational view of the alarm clock of the second embodiment;

FIG. 10 is a right side elevational view of the alarm clock of the second embodiment;

FIG. 11 is a left side elevational view of the alarm clock of the second embodiment;

FIG. 12 is a top plan view of the alarm clock of the first embodiment; and,

FIG. 13 is a bottom plan view of the alarm clock of the first embodiment.

The broken lines shown are for illustrative purposes only and form no part of the claimed design.
